ATTORNEY.

UNITED STATES PATENT OFFICE.

JOHN PHIL. BANNIGAN, OF UTICA, NEW YORK, ASSIGNOR OF TWO-THIRDS TO
FREDERICK B. ADAMS AND DAVID J. GOLDSTEIN, BOTH OF UTICA, NEW
YORK.

LETTER-REPRODUCING DEVICE.

1,427,254.

Specification of Letters Patent. Patented Aug. 29, 1922.

Application filed August 6, 1920. Serial No. 401,684.

To all whom it may concern:

Be it known that I, JOHN PHIL. BANNIGAN, a citizen of the United States, residing at Utica, in the county of Oneida and State of New York, have invented certain new and useful Improvements in Letter-Reproducing Devices, of which the following is a specification, reference being had therein to the accompanying drawing.

10 My invention relates to a letter reproducing device, and I declare the following to be a full, complete and concise description thereof sufficient to enable anyone skilled in the art to which it appertains to make and 15 use the same, reference being had to the accompanying drawings in which like reference characters refer to like parts throughout the specification.

The object of my invention is to provide 20 a machine that will reproduce writings or drawings or any matters that can be perforated through a stencil, whereby a plurality of copies of a given subject matter can be made for any desired purpose.

25 The invention comprises a frame having a perforated circular base that is covered with an absorbent material, such as cloth adapted to retain ink thereon. Over this cloth, is removably held a paper or wax 30 stencil that is perforated to conform with the subject matter to be reproduced. The stencil is held in place by certain members of a vertically movable handle.

The object will appear by referring to the 35 drawings in which:

Fig. 1 is a perspective view of the device;

Fig. 2 is a central vertical section taken on the line 2—2 of Fig. 3;

Fig. 3 is a top plan view of the letter 40 reproducing device.

Referring more particularly to the drawings, the device embodies a circular base plate —1— made of sheet metal and having perforations or apertures 2 arranged more or less in groups over its entire surface. 45 The apertures 2 are adapted for the passage of ink to the absorbent cloth 3 therebelow. Furthermore, the lateral edges of the plate —1— are turned up at an angle, as at 7—7, 50 in order to prevent the escape of ink past the sides of the plate —1—.

The free ends 4—4 of the plate —1— are bent at an angle, whereby to form a horizontal plane. The cloth 3 is stretched over 55 the convex surface of the plate —1— and its

free ends glued or otherwise fastened to the horizontal parts of the ends 4—4 of plate —1—.

A floating double T shaped plate 5 preferably made of sheet metal is mounted, whereby its ends will make contact with the under surface of the ends 4—4 of plate —1—.

Plate 5 is reinforced in the center part thereof by an annular metal ring piece 6 that is spot welded to said plate 5. A screw 65 threaded aperture is made in alignment through the plate 5 and ring piece 6 for the reception of a screw bolt 8 that has attached to turn therewith an annular thumb piece 9 having a serrated periphery adapted to aid 70 in turning said bolt 8.

The upper end of the bolt 8 is headed at 10. The head rests upon a washer 11 through which the shank of the bolt 8 projects. The head 10 of the bolt 8 and the 75 washer 11 are housed in a recess 12 made in the wooden handle 13. The washer 11 forms a bearing surface for the head 10 of the bolt 8 to turn on. The recess 12 is covered by a metal plate 14 that is fastened to the 80 wooden surface of the handle 13 by sharp points 15 that project from the under surface of said plate 14.

The ends of the handle 13 rest in the metal 85 rings 16—16 that are made integral with the brackets 17—17. The free end of each of the brackets 17 is formed with a horizontal plane surface 18 adapted to lie in a plane parallel with the upper surface of the ends 4—4 of base plate —1—, whereby the ends 90 of a paper or wax stencil 20 can be clamped between the under surface of the said members 18 and the ends of the cloth 3 that rests upon the horizontal portions of the ends 4—4 of plate —1—.

The handle 13 and members 18 attached thereto are lowered and raised from full to dotted line position as shown in Fig. 2, whereby to fasten or release the ends of a paper stencil 20 by turning the bolt 8 in the 100 desired direction.

The device is operated by first making a paper stencil 20 that conforms to the letter or other matter to be reproduced and then fastening said stencil 20 upon the convex 105 surface of the base plate —1— and over the absorbent cloth 3 by engaging the ends thereof between the under surface of members 18—18 and the upper surface of cloth 3 that rests upon the ends 4—4 of plate —1—. 110

The thumb piece 9 will be turned to lower the members 18-18 and raise the plate 5 against the lower surfaces of the ends 4-4 of plate 1, whereby to clamp the ends 5 of the stencil 20 in this position.

The stencil 20 will receive ink from the absorbent cloth 3, whereby to make an impression of the matter to be reproduced on the paper sheets, not shown, therebeneath, 10 as the device is rocked thereover by means of the handle 13. In the event that certain portions of the stencil 20 leave a poor or dull impression of parts of the written matter on the stencil, more ink can be added to the 15 cloth directly over said spots and without detaching said stencil 20 by placing ink preferably with a brush upon the near surface of the plate 1 and over said dull spots, whereby it will pass through the 20 perforations 2 to the desired location on the absorbent cloth 3.

Stencil 20 can be replaced easily with another by turning the thumb piece 9 to raise and lower the members 18 off the ends of 25 said stencil 20.

Having thus described my invention what I claim as new and desire to secure by Letters Patent is:

1. In a letter reproducing device, a frame 30 having a circular base, an absorbent cloth and stencil adapted to cover said base, means for permitting the passage of ink through said frame to said cloth, the free ends of said frame being bent to form a horizontal 35 plane, a floating plate, a handle disposed in longitudinal position relative said frame, and having brackets with plane surfaces, and a bolt for forcing the ends of said plate against the ends of said frame, whereby to 40 clamp the ends of said cloth and stencil in place between the floating plate and the plane surfaces of the brackets.

2. In a letter reproducing device, a frame 45 having its free ends bent to form a horizontal plane, an absorbent cloth and stencil adapted to cover said base, perforations in said frame for the passage of ink to said cloth, the free ends of said frame being bent to form a horizontal plane, a floating plate, 50 a handle having brackets with plane surfaces and disposed in a longitudinal position relative to said frame, a screw bolt for forcing the ends of said plate against the ends of said frame, whereby to clamp the ends of 55 said cloth and stencil between said floating plate and the plane surfaces of the brackets, and an annular thumb piece for turning said bolt.

3. In a letter reproducing device, a frame 60 having a circular base forming a chamber, an absorbent cloth and stencil adapted to cover said base, perforations in said frame for the passage of ink to said cloth, the free

ends of said frame being bent to form a horizontal plane, a floating plate, a bolt 65 screw threaded to said plate, and an annular thumb piece for turning said bolt, whereby to clamp the ends of said cloth and stencil between the floating plate and the plane surfaces of the brackets. 70

4. In a letter reproducing device, a frame having a circular base with its sides turned up to form a chamber, an absorbent cloth and stencil adapted to cover said base, perforations in said frame for the passage of ink to said cloth, the free ends of said frame being bent to form a horizontal plane, a floating plate whose ends are adapted to make contact with the ends of said frame, a handle disposed in longitudinal position 80 with reference to said frame and having brackets with plane surfaces, a screw bolt carried by said handle, whereby to force the ends of said plate and the plane surfaces of said brackets towards each other to clamp 85 the ends of the cloth and stencil between said plane surfaces and the ends of the frame.

5. In a letter reproducing device, a frame having a circular base, an absorbent cloth 90 and stencil adapted to cover said base, perforations in said frame for the passage of ink to said cloth, the free ends of said frame being bent to form a horizontal plane, a floating plate whose ends are adapted to 95 make contact with the ends of said frame, a handle having brackets with plane surfaces, a screw bolt carried by said handle, whereby to force the ends of said plate towards the plane surfaces of said brackets to 100 clamp the ends of the frame, and an annular thumb piece carried by said bolt for turning the same.

6. In a letter reproducing device, a frame having a circular base with its edges turned up, an absorbent cloth and stencil adapted to cover said base, perforations in said frame for the passage of ink to said cloth, the free ends of said frame being bent to form a horizontal plane, a floating plate whose ends are adapted to make contact with the ends of said frame, a handle disposed in longitudinal position with reference to said frame, brackets with plane surfaces for supporting said handle, a screw bolt carried by said handle, whereby to force the ends of said plate towards the plane surfaces of said brackets to clamp the ends of the cloth and stencil between said plane surfaces and the ends of the frame, an annular thumb piece carried by said bolt for turning the same, and said thumb piece being located adjacent said handle. 105 110 115 120

In testimony whereof I have affixed my signature.

J. PHIL. BANNIGAN.
